Primary Examiner — Paula Greene

(57) **CLAIM**

The ornamental design for a storage device, as shown and described.

DESCRIPTION

FIG. 1 is a top, front and side perspective view of a first embodiment of a storage device embodying the new design. FIG. 2 is a front view thereof.

FIG. 3 is a back view thereof.

FIG. 4 is a first side view thereof.

FIG. 5 is a second side view thereof.

FIG. 6 is a top view thereof; and,

FIG. 7 is a bottom view thereof.

Broken lines are used to illustrate features of the storage device which form no part of the claimed design.
